[57]

CLAIM

A bipolar electrical surgical generator, substantially as shown.

DESCRIPTION

FIG. 1 is a perspective view of a bipolar electrical surgical generator showing my new design;
FIG. 2 is a top plan view of the generator shown in FIG. 1;
FIG. 3 is an end view of the generator shown in FIG. 1;
and
FIG. 4 is a rear view of the generator shown in FIG. 1.

fig. 1.

fig. 2.

Fig. 3.

Fig. 4.

[57] CLAIM

A bipolar electrical surgical generator, substantially as shown.

DESCRIPTION

FIG. 1 is a perspective view of a bipolar electrical surgical generator showing my new design;
FIG. 2 is a top plan view of the generator shown in FIG. 1;
FIG. 3 is an end view of the generator shown in FIG. 1;
and
FIG. 4 is a rear view of the generator shown in FIG. 1.

Reexamination Certificate for:

Patent No.: Des. 250,480

Issued: Dec. 5, 1978

Appl. No.: 767,896

Filed: Feb. 11, 1977

[52] U.S. Cl. D24/170

[58] Field of Search D24/170

**REEXAMINATION CERTIFICATE
ISSUED UNDER 35 U.S.C. 307****THE PATENT IS HEREBY AMENDED AS
INDICATED BELOW.****AS A RESULT OF REEXAMINATION, IT HAS
BEEN DETERMINED THAT:**

5 The single claim is cancelled.
